S. J. STONE.

BILL HOLDER,

APPLICATION FILED FEB. 8, 1915.

1,227,339.

Patented May 22, 1917

UNITED STATES PATENT OFFICE.

SAMUEL J. STONE, OF TIPPECANOE CITY, OHIO.

BILL-HOLDER.

1,227,339.

Specification of Letters Patent. Patented May 22, 1917.

Application filed February 8, 1915. Serial No. 6,907.

To all whom it may concern:

Be it known that I, SAMUEL J. STONE, a citizen of the United States, residing at Tippecanoe City, in the county of Miami and State of Ohio, have invented certain new and useful Improvements in Bill-Holders; and I do hereby declare the following to be a full, clear, and exact description of the invention, such as will enable others skilled in the art to which it appertains to make and use the same.

This invention has for its object to provide efficient and inexpensive means for reliably securing bill holders, or frames, to trees, posts, poles and the like.

With this and other objects in view, the invention consists in the novel construction, arrangement and formation of parts as will be hereinafter specifically described, claimed and illustrated in the accompanying drawing, in which:

Figure 1 represents a perspective view of the improved holder applied to use.

Fig. 2 represents a horizontal sectional view therethrough.

Fig. 3 represents a vertical sectional view through the holder, and

Fig. 4 represents a fragmental elevation of the rear of the frame.

Referring to the drawing in detail, wherein similar reference numerals designate corresponding parts throughout the several views, the numeral 5 indicates a frame formed of wood or any other suitable material having a recess 6 formed in the rear portion thereof to receive a bill 7 or card bearing advertising or other printed matter, which is secured in position in the recess 6 by strips 8.

The frame is reliably secured in the de-

sired position upon a post, pole, fence paling, or the like 9 by nails or equivalent securing devices 10, which are driven through the upper and lower horizontal members of the frame and into the object 9. The frame 45 is prevented from rocking or swinging upon the object 9 by a plurality of wires 11 secured at their outer ends to eye bolts 12 secured in the vertical members of the frame 5, and the inner ends of the bracing wires 11 50 are coiled about and secured to the shank of a nail or equivalent securing device 13 having a head 14 to prevent the coiled ends of the wires from slipping therefrom. It is clearly evident that the nails or equivalent securing devices 10 reliably secure the frame 5 against vertical movement upon the post, or other object 9, while the bracing wires 11 55 reliably secure the sign against rocking movement upon the object. 60

What I claim is:

In combination, a post, a flat frame positioned against said post and including vertical and horizontal members, eye-bolts secured to the vertical members of said frame, 65 a headed fastener secured in said post behind said frame, fastening wires coiled about said fastener and positioned under the head thereof and having the outer ends secured to said eye-bolts to prevent swinging movement of the frame, and means positioned through the horizontal members of the frame and the post to rigidly hold the frame against vertical movement thereon. 70

In testimony whereof I affix my signature 75 in presence of two witnesses.

SAMUEL J. STONE.

Witnesses:

ELLIS H. KERR,
PHOEBE RATCLIFF.
